ABSTRACT OF THE DISCLOSURE

Increasing the sugar content of sugar cane by contacting the sugar cane with substituted benzenesulfonyl ureas and its salts.

This application is a continuation-in-part of application Ser. No. 582,223, filed Sept. 27, 1966, now abandoned.

In accordance with this invention, the sugar content of sugar cane is increased by a method which comprises applying to maturing sugar cane one or more compounds selected from the group consisting of

(I) Compounds having the formula

and

wherein X is selected from the group consisting of chloro, bromo, iodo and fluoro; Y is selected from the group consisting of alkyl, alkoxy, alkenyl and alkynyl each of which has a maximum of 12 carbon atoms; Z is selected from the group consisting of NO_2 , NH_2 , NO, CN and

wherein R is selected from the group consisting of hydrogen and alkyl having a maximum of 12 carbon atoms; a is an integer from 0 to 5, inclusive; b is an integer from 0 to 3, inclusive; c is an integer from 0 to 1, inclusive; M is a salt-forming cation selected from the group consisting of alkali metals, alkaline earth metals, ammonium and aliphatic-substituted ammoniums; and n is the valence of M, said compound being applied in an amount sufficient to increase the sugar content of the sugar cane but in an amount insufficient to exert a herbicidal action.

In the above formula Y can be alkyl such as methyl, ethyl, n-propyl, isopropyl, n-butyl, sec-butyl, isobutyl, tert-butyl, amyl, hexyl, heptyl, octyl, nonyl, decyl, dodecyl and the various homologues and isomers of alkyl having not more than 12 carbon atoms, alkenyl such as vinyl allyl, n-butenyl-1, n-butenyl-2, n-pentenyl-2, n-hexenyl-2, 2,3-dimethylbutenyl-2, n-heptenyl, n-decenyl, n-dodecenyl and the various homologues and isomers of alkenyl having not more than 12 carbon atoms, alkynyl such as ethynyl, propargyl, 3-hexynyl and the various homologues and isomers of alkynyl having not more than 12 carbon atoms, and alkoxy such as methoxy, ethoxy, butoxy, hexoxy, heptoxy and the various homologues and isomers of alkoxy having not more than 12 carbon atoms. R as alkyl can be any of the alkyl listed above for Y.

2

The aliphatic-substituted ammonium salts are those prepared from low molecular weight aliphatic amines, i.e., having a molecular weight below about 300, and more particularly the alkyl amines, alkylene amines and alkanol amines containing not more than 2 amine groups such as 5 methylamine, ethylamine, n-propylamine, isopropylamine, n-butylamine, isobutylamine, sec-butylamine, n-amylamine, iso-amylamine, hexylamine, heptylamine, octylamine, nonylamine, decylamine, undecylamine, dodecylamine, tridecylamine, tetradecylamine, pentadecylamine, hexadecylamine, heptadecylamine, octadecylamine, methylethylamine, methylisopropylamine, methylhexylamine, methylnonylamine, methylpentadecylamine, methyloctadecylamine, ethylbutylamine, ethylheptylamine, 15 ethyloctylamine, hexylheptylamine, hexyloctylamine, dimethylamine, diethylamine, di-n-propylamine, diisopropylamine, di-n-butylamine, diisobutylamine, di-sec-butylamine, di-n-amylamine, diisoamylamine, dihexylamine, diheptylamine, dioctylamine, trimethylamine, 20 triethylamine, tri-n-propylamine, triisopropylamine, tri-n-butylamine, triisobutylamine, tri-sec-butylamine, tri-n-amylamine, ethanolamine, n-propanolamine, isopropanolamine, diethanolamine, tri-N-ethylethanolamine, N-ethylpropanolamine, N-butylethanolamine, allylamine, n-but enyl-2-amine, n-pentenyl-2-amine, 2,3-dimethylbutenyl-2-amine, dibutenyl-2-amine, n-hexenyl-2-amine, and propylenediamine.

The preferred compounds are selected from the group consisting of

wherein X is selected from the group consisting of chloro, bromo, iodo and fluoro; a is an integer 0 to 2, inclusive; Y is selected from the group consisting of alkyl and alkoxy having a maximum of four carbon atoms; b is an integer 0 to 1, inclusive; Z is selected from the group consisting of NO_2 , NH_2 and

50 wherein R is selected from the group consisting of hydrogen and alkyl having a maximum of 5 carbon atoms; c is an integer 0 to 1, inclusive, M is selected from the group consisting of alkali metal, alkaline earth metal, ammonium and substituted ammonium of the formula

wherein R², R³ and R⁴ are each independently selected from the group consisting of hydrogen, alkyl, alkenyl and hydroxyalkyl each having a maximum of 4 carbon atoms.

60 It is known that the anionic portion of the salts is a resonance hybrid having the terminology of "isourea" and "urea" depending upon the charge location. For convenience the terminology of "isourea" will be used in this specification and appended claims to designate the salts of the resonance hybrid, and the term "urea" will be used to designate the free base.

65 The ureas and isourea salts are applied to the maturing sugar cane prior to the time the sugar cane has reached maximum sugar content or the complete ripening thereof. The application of the ureas and isourea salts to sugar cane is carried out at more than about one week prior

to harvest but not more than about 4 months prior to harvest. Application not more than about 2 months prior to harvest is particularly advantageous.

As mentioned hereinbefore, the ureas and isourea salts are applied in an amount sufficient to increase the sugar content of the sugar cane, but in an amount insufficient to exert a herbicidal action. Such amounts are determined by and dependent upon the particular urea or isourea salt selected, the method of application, the state and condition of growth of the sugar cane, and the climatic conditions. An increase in sugar content of sugar cane without herbicidal action is obtained in most instances by the application of the ureas or isourea salts in an amount from about 0.1 to about 10 pounds per acre. The preferred application rate is from about 3 pounds to about 7 pounds of isourea salt per acre.

The isourea salts useful in the methods of this invention and processes for making them are well known in the art. They can be prepared by reacting an arylsulfonamide with a suitable cyanate. For example, potassium 1-(p-nitrobenzenesulfonyl) isourea can be prepared by heating substantially equimolar amounts of p-nitrobenzenesulfamide and potassium cyanate in the presence of an aqueous medium under reflux for about 8 hours, cooling the reaction mixture and recovering the product by filtration. More detailed procedures for the preparation of various p-substituted benzenesulfonylisourea salts are set forth in Martin et al. U.S. Pat. 2,411,661 (Nov. 26, 1946) and Haack U.S. Pat. 2,385,571 (Sept. 25, 1945), and the disclosures thereof are incorporated herein by reference.

The following examples illustrate the invention. Parts and percent are by weight unless otherwise indicated.

EXAMPLE 1

Six month old sugar cane (Pinder) plants grown under greenhouse conditions at a temperature from about 70° F. to about 90° F. and 65% relative humidity are sprayed with acetone-water solutions containing a small amount of emulsifier and various amounts of calcium 1-(p-nitrobenzenesulfonyl) isourea at a rate equivalent to about 70 gallons of spray per acre. The sprays are applied at rates of one and ten pounds of isourea salt per acre using Randomized Block with six replications of each application rate including control (no active ingredient). Harvesting is carried out three weeks after spraying and the amount of sucrose is measured and recorded. Results and further details are given in Table I wherein results are expressed as a percent of the control.

TABLE I

Application rate, lb./acre:	Total wt. of sucrose per stalk	
	Control (0)	100
Control (0)	100	100
1	114	114
10	143	143

EXAMPLE 2

The spraying procedure of Example 1 is repeated at a rate of about 5 pounds of calcium 1-(nitrobenzenesulfonyl) isourea per acre. After spraying, the sugar cane plants are held at a temperature of about 79° F. over the 12-hour "daylight" period and about 72° F. over the 12-hour "night" period. Harvesting is carried out with different groups of plants at intervals of 4 weeks and 8 weeks after spraying. Results and further details are given in Table II below wherein all results are expressed as a percent of the control.

TABLE II.—PERCENT FRESH WEIGHT OF SUCROSE IN STALKS

Application rate, lb./acre	Harvest	
	4 weeks	8 weeks
Control (0)	100	100
5	134	163

EXAMPLE 3

Repeating Example 1, using p-aminobenzenesulfonylurea (A) or potassium 1-(p-bromobenzenesulfonyl)-isourea (B) in place of the calcium derivative yielded the results, in percent of the control, listed in Table III.

TABLE III

Application rate, lb./acre	Total Weight of Sucrose Per Stalk	
	(A)	(B)
Control (0)	100	100
1	117	109
4	121	104
8	128	103

The increase in sugar content exhibit in Tables I, II and III was brought about without herbicidal action on the sugar cane.

Other ureas and isourea salts of the above formulae which can be used in accordance with the methods of this invention to increase the sugar content of sugar cane include the following:

calcium 1-(p-chlorobenzenesulfonyl) isourea
calcium 1-(p-methylbenzenesulfonyl) isourea
sodium 1-(p-nitrobenzenesulfonyl) isourea
25 sodium 1-(p-methoxybenzene sulfonyl) isourea
magnesium 1-(p-chlorobenzenesulfonyl) isourea
magnesium 1-(p-butynyl-2-benzenesulfonyl) isourea
calcium 1-(p-aminobenzenesulfonyl) isourea
30 calcium 1-(p-cyanobenzenesulfonyl) isourea
sodium 1-(p-chlorobenzenesulfonyl) isourea
magnesium 1-(3,4-dichlorobenzenesulfonyl) isourea
potassium 1-(p-nitrosobenzenesulfonyl) isourea
sodium 1-(p-chlorobenzenesulfonyl) isourea
calcium 1-(3,4-dichlorobenzenesulfonyl) isourea
35 calcium 1-(p-acetylaminobenzenesulfonyl) isourea
magnesium 1-(p-nitrobenzenesulfonyl) isourea
magnesium 1-(3,4,5-trichlorobenzenesulfonyl) isourea
barium 1-(p-aminobenzenesulfonyl) isourea
magnesium 1-(p-aminobenzenesulfonyl) isourea
40 magnesium 1-(3-aminobenzenesulfonyl) isourea
ammonium 1-(p-nitrobenzenesulfonyl) isourea
ammonium 1-(2,4-dimethylbenzenesulfonyl) isourea
ethylamine salt of p-nitrobenzenesulfonyl isourea
diethylamine salt of p-nitrobenzenesulfonyl isourea
45 triethylamine salt of p-nitrobenzenesulfonyl isourea
N-methylethylamine salt of p-nitrobenzenesulfonyl isourea
ethanolamine salt of p-nitrobenzenesulfonyl isourea
diethanolamine salt of p-nitrobenzenesulfonyl isourea
ethanolamine salt of p-aminobenzenesulfonyl isourea
50 allylamine salt of p-nitrobenzenesulfonyl isourea
ethanolamine salt of p-acetylaminobenzenesulfonyl isourea
diethylamine salt of n-butylcarbonylaminobenzenesulfonyl isourea
55 p-aminobenzenesulfonyl urea
p-nitrobenzenesulfonyl urea
p-chlorobenzenesulfonyl urea
3,4-dichlorobenzenesulfonyl urea
60 p-nitrosobenzenesulfonyl urea
p-acetylbenzenesulfonyl urea
p-cyanobenzenesulfonyl urea
3,4,5-trichlorobenzenesulfonyl urea
p-methylbenzenesulfonyl urea
65 p-methoxybenzenesulfonyl urea
2,4-dimethylbenzenesulfonyl urea
p-n-butynyl-2-benzenesulfonyl urea

For the sake of brevity, the term "active ingredient" is used hereinafter in this specification to describe the ureas and isourea salts useful in accordance with the methods of this invention.

In practicing the methods of this invention, the active ingredients can be used alone or in combination with an adjuvant in liquid or solid form. The compositions are prepared by admixing the active ingredient with an

adjuvant including diluents, extenders, spreaders, adhesives, carriers and conditioning agents to provide compositions in the form of finely-divided particulate solids, solutions, dispersions or emulsions. Thus the active ingredient can be used with an adjuvant such as a finely-divided particulate solid, a liquid of organic origin, water, a wetting agent, dispersing agent, an emulsifying agent or any suitable combination of these.

Typical finely-divided solid carriers and extenders which can be used in the compositions of this invention include, for example, the talcs, clays, pumice, silica, lime, calcium carbonate, diatomaceous earth, quartz, fuller's earth, salt, sulfur, powdered cork, powdered wood, cotton seed hulls, wheat flour, soybean flour, walnut flour, chalk, tobacco dust, volcanic ash, charcoals and the like. Typical liquid diluents include for example, water, kerosene, Stoddard solvent, hexane, benzene, toluene, acetone, ethylene dichloride, xylene, alcohols, diesel oil, glycols and the like.

The compositions useful in this invention, particularly liquids and wettable particles, usually contain as a conditioning agent one or more surface-active agents in amounts sufficient to render a given composition readily dispersible in water or in oil. By the term "surface-active agent" it is understood that wetting-agents, dispersing agents, suspending agents and emulsifying agents are included therein.

Preferred compositions containing the active ingredients have been developed so that the active ingredients can be used to the greatest advantage to increase the sugar content of sugar cane. The preferred compositions comprise certain wettable powders, aqueous suspensions, dust formulations, emulsifiable oils and solutions in solvents. In general these preferred compositions all contain one or more surface-active agents.

Surface-active agents which can be used in the compositions useful in this invention are set out, for example, in Searle U.S. Pat. 2,426,417, Todd U.S. Pat. 2,655,447, Jones U.S. Pat. 2,412,510 and Lenher U.S. Pat. 2,139,276. A detailed list of such agents is also set forth by J. W. McCutcheon in "Soap and Chemical Specialties," November 1947, page 8011 et seq., entitled "Synthetic Detergents"; "Detergents and Emulsifiers—Up to Date" (1960), by J. W. McCutcheon, Inc., and Bulletin E-607 of the Bureau of Entomology and Plant Quarantine of the U.S.D.A. In general, less than 50 parts by weight of the surface-active agents is present per 100 parts by weight of the composition.

Wettable powders are water-dispersible compositions containing one or more active ingredients, an inert solid extender and one or more wetting and dispersing agents. The inert solid extenders are usually of mineral origin such as the natural clays, diatomaceous earth and synthetic minerals derived from silica and the like. Examples of such extenders include kaolinites, attapulgite clay and synthetic magnesium silicate.

Preferred wetting agents are alkali metal alkylaryl sulfonates, sulfated fatty alcohols, amines or acid amides, long chain acid esters of sodium isethionate, esters of sodium sulfosuccinate, sulfated or sulfonated fatty acid esters, petroleum sulfonates, sulfonated vegetable oils, tertiary acetylinic glycols, polyoxyethylene derivatives of alkylphenols (particularly iso-octylphenol and nonylphenol) and polyoxyethylene derivatives of mono-higher fatty acid esters of hexitol anhydrides (e.g. sorbitan). Preferred dispersants are methyl cellulose, polyvinyl alcohol, sodium lignin sulfonates, polymeric alkyl naphthalene sulfonates, sodium naphthalene sulfonate, polymethylene bisnaphthalenesulfonate and sodium N-methyl-N-(long chain acid) taurates.

The wettable powder compositions usually contain from about 5 to about 95 parts of active ingredient, from about 0.25 part to about 25.0 parts of wetting agent, from about 0.25 part to about 7 parts of dispersant and from about 4.5 to about 94.5 parts of inert solid extender, all parts

being by weight of the total composition. Where required from about 0.1 to 2.0 parts by weight of the solid inert extender can be replaced by a corrosion inhibitor or anti-foaming agent or both. If the particular active ingredient selected is water-soluble, the solution formed by admixture with water or other aqueous media can be employed in the methods of this invention without further formulation.

Emulsifiable oils are usually solutions of active ingredient in water-immiscible solvents together with a surfactant. Suitable surfactants are anionic, cationic and non-ionic such as alkylaryl polyethoxy alcohols, polyethylene sorbitol or sorbitan fatty acid esters, polyethylene glycol fatty esters, fatty alkylol amide condensates, amine salts of fatty alcohol sulfates together with long chain alcohols and oil soluble petroleum sulfonates or mixtures thereof. The emulsifiable oil compositions generally contain from about 5 to 95 parts active ingredient, about 1 to 50 parts surfactant and about 4 to 94 parts solvent, all parts being by weight based on the total weight of emulsifiable oil.

When operating in accordance with the present invention, effective amounts of the active ingredients are applied to sugar cane plants in any convenient fashion. The application of the compositions to the sugar cane can be carried out by conventional methods, e.g., power dusters, boom and hand sprayers and spray dusters. The compositions can also be applied from airplanes as a dust or a spray because of their effectiveness at low dosages.

Herbicidal compositions containing as an active ingredient therein many of the above ureas and isourea salts are disclosed and claimed in copending application Ser. Nos. 210,220 and 210,242, both filed July 16, 1962, and copending application Ser. No. 406,884, filed Oct. 25, 1964, which in turn is a division of application Ser. No. 210,217, filed July 16, 1962, and now abandoned.

The terms "amine" and "aliphatic substituted ammonium" as used herein mean only those ammonium and amine compounds wherein each valence of the nitrogen atom is attached to a different hydrogen or carbon atom.

Although the invention is described with respect to specific modifications, the details thereof are not to be construed as limitations except to the extent indicated in the following claims.

While the illustrative embodiments of the invention have been described hereinbefore with particularity, it will be understood that various other modifications will be apparent to and can readily be made by those skilled in the art without departing from the scope and spirit of the invention.

What is claimed is:

1. Method of increasing the sugar content of sugar cane which comprises applying to sugar cane a compound selected from the group consisting of compounds having the formula

55 (a)

and

60 wherein R' is selected from the group consisting of chloro, bromo, fluoro, iodo, nitro and —NH₂; M is a salt-forming cation selected from the group consisting of alkali metals, alkaline earth metals, ammonium and substituted ammonium of the formula

70

wherein R², R³ and R⁴ are each independently selected from the group consisting of hydrogen, alkyl, alkenyl and hydroxyalkyl each having a maximum of 4 carbon atoms; and n is the valence of M, said compound being

applied, not more than 4 months prior to harvest, in an amount sufficient to increase the sugar content of the sugar cane but in an amount insufficient to exert a herbicidal action.

2. Method of claim 1 wherein R' is NO₂.
3. Method of claim 1 wherein R' is NH₂.
4. Method of claim 1 wherein R' is chloro.
5. Method in accordance with claim 1, in which the compounds have the formula

wherein R' is selected from the group consisting of chloro, bromo, fluoro, iodo, nitro and —NH₂.

6. Method of claim 5 wherein the compound is p-aminobenzenesulfonyl urea.

7. Method in accordance with claim 1, in which the compounds have the formula

wherein R' is selected from the group consisting of chloro, bromo, fluoro, iodo, nitro and —NH₂; M is a salt-forming cation selected from the group consisting of alkali

metals, alkaline earth metals, ammonium and substituted ammonium of the formula

- 5 wherein R², R³ and R⁴ are each independently selected from the group consisting of hydrogen, alkyl, alkenyl and hydroxyalkyl each having a maximum of 4 carbon atoms; and n is the valence of M.

8. Method of claim 7 wherein the compound is calcium

- 10 1-(p-nitrobenzenesulfonyl)isourea.

9. Method of claim 7 wherein the compound is calcium 1-(p-aminobenzenesulfonyl)isourea.

10. Method of claim 7 wherein the compound is calcium 1-(p-chlorobenzenesulfonyl)isourea.

- 15 11. Method of claim 7 wherein the compound is the ethanolamine salt of p-nitrobenzenesulfonyl isourea.

12. Method of claim 7 wherein the compound is potassium 1-(p-bromobenzenesulfonyl)isourea.
